UNITED STATES PATENT OFFICE

115,326

DESIGN FOR A DENTAL TOOL

Edward L. Chott, Chicago, Ill.

Application December 30, 1938, Serial No. 82,091

Term of patent 14 years

To all whom it may concern:

Be it known that I, Edward L. Chott, a citizen of the United States, residing in Chicago, in the county of Cook and State of Illinois, have invented a new, original, and ornamental Design for a Dental Tool, of which the following is a specification, reference being had to the accompanying drawing, forming a part thereof, in which:

Figures 2 and 3 are sectional views taken on the section lines 2—2 and 3—3 respectively, of Figure 1.

I claim:

The ornamental design for a dental tool, as shown.

EDWARD L. CHOTT.
